UNITED STATES PATENT OFFICE.

WILLIAM S. LOUGEE, OF ROCHESTER, NEW HAMPSHIRE, ASSIGNOR TO KENNEBUNK MANUFACTURING COMPANY, OF KENNEBUNK, MAINE, A CORPORATION OF MAINE.

DESIGN FOR A MEGAPHONE.

46,404.

Specification for Design.

Patented Sept. 15, 1914.

Application filed December 14, 1911. Serial No. 665,820. Term of patent 7 years.

To all whom it may concern:

Be it known that I, WILLIAM S. LOUGEE, a citizen of the United States, residing at Rochester, in the county of Strafford and State of New Hampshire, have invented a new, original, and ornamental Design for a Megaphone, of which the following is a specification, reference being had to the accompanying drawing, forming part thereof.

In the drawings, Figure 1 is an elevation of a megaphone, and Fig. 2 is a perspective view of the megaphone mouth-piece, showing my new design.

I claim:

The ornamental design for a megaphone, as shown.

WILLIAM S. LOUGEE.

Witnesses:

SAMUEL D. FELKER,

WILLIAM T. GUNNISON.
